UNITED STATES PATENT OFFICE.

ROBERT M. DOWNE, OF BEAVER FALLS, PENNSYLVANIA, ASSIGNOR TO
KEYSTONE DRILLER CO., OF BEAVER FALLS, PENNSYLVANIA, A COR-
PORATION OF PENNSYLVANIA.

CORE-DRILL.

No. 848,227.

Specification of Letters Patent.

Patented March 26, 1907.

Application filed February 26, 1906. Serial No. 303,096.

To all whom it may concern:

Be it known that I, ROBERT M. DOWNE, a citizen of the United States, residing at Beaver Falls, in the county of Beaver and State of Pennsylvania, have invented a new and useful Core-Drill, of which the following is a specification.

In core-drills, particularly those of the percussion type, a number of objections are present. In the first place the structure of the cutters is ordinarily such that they stick fast in the well, and this is due to the fact that sufficient play has not heretofore been secured to permit them to cut a hole large enough for their necessary movement. Another trouble has been in providing a structure that will cut beneath the lower end of the core-barrel, and thus produce a core of small enough diameter to enter such barrel. Finally, as the drill-stem is in the form of a tube or casing the strength of the joint between the same and the cutter is limited by the thinness of the former. It has therefore been impossible to wrench up the joints tight enough to prevent them becoming loosened and unscrewed by the cutting of the stroke.

It is the principal object to provide by this invention a novel structure which is not only effective as a core-drill, but which will eliminate the above-noted serious objections.

The preferred embodiment of the invention is illustrated in the accompanying drawings, wherein—

Figure 1 is a view, partly in elevation and partly in section, of the lower portion of a core-drill. Fig. 2 is a side elevation, on an enlarged scale, of the cutter. Fig. 3 is a bottom plan view of said cutter. Fig. 4 is a longitudinal sectional view through the same. Fig. 5 is a detail sectional view illustrating the structure when in use and in a well. Fig. 6 is a similar view taken at right angles to Fig. 5. Fig. 7 is a horizontal sectional view taken substantially on line 7-7 of Fig. 6. Similar reference-numerals designate corresponding parts in all the figures of the drawings.

In the embodiment illustrated a portion of a reciprocatory drill-stem is shown and is designated 8, said stem, as usual, being in the form of a tube. Within the stem is slidably mounted a core-receiving tube or core-barrel 9, the said barrel being of less diameter than

the bore of the tubular stem, and said stem being capable of a lateral movement with respect to the barrel. A cutter 10 is carried by the lower end of the stem and comprises a tubular body 11, having an upstanding portion 12, which is exteriorly threaded and is screwed into the lower end of the stem. The barrel 9 is slideable through the cutter-body and is of less diameter than the bore of the same, so that said cutter can swing laterally with the stem and with respect to the barrel.

Carried by the lower end of the cutter-body 11 are sets of tooth members 12^a and 13. The members of each set are located on diametrically opposite sides of the body, and the members of the different sets have their central portions disposed substantially ninety degrees apart. Each tooth member is provided with one or a plurality of cutting-teeth 14 and 15. The teeth of one set of members are inwardly inclined or set inwardly, while those on the other set of members are outwardly inclined, the tooth or teeth of each member thus being correspondingly arranged. As a result of this construction it will be observed that on two sides of the body the teeth, as 14, are outwardly set, while on the other two sides the teeth are inwardly set. The distance between the diametrically opposite inset teeth are at their cutting-points substantially the same as the diameter of the core-receiving barrel 9. This particular arrangement has decided advantages, for it will be apparent that at two diametrically opposite sides only will the outset teeth of the drill touch the outer wall of the bore-hole, and in like manner the inwardly-set teeth, being located on two sides only of the drill, will engage the core on but two sides. This arrangement therefore allows the lateral jostling of the drill with respect to the core-barrel, and consequently with respect to the core received therein. Thus not only will the drill-hole or well be made of greater diameter than the drill, but the core will be formed of less diameter than the bore thereof. It is believed that this will be clear by reference to Fig. 5.

It will be noted that when one set of outwardly-flared teeth are against the outer wall of the drill-hole the other set will be spaced therefrom, and this lateral movement will also cause the lateral movement of the in-

wardly-set teeth, causing said inwardly-set teeth to jostle back and forth and operate beneath the lower end of the core-barrel, as shown in Fig. 6. The result is that the core 5 will be trimmed down to the diameter of the barrel, and the latter will consequently receive the same without difficulty. This core-barrel may be provided with a suitable clutch-ring, (shown at 16 in Figs. 5 and 6,) so 10 that when the drill is elevated the core will be retained within the barrel and lifted with it. The jostling or lateral shifting movements thus allowed to the drill will in practice cause the same as a whole to cut a hole 15 somewhat larger than a diameter represented by the distance between the outside cutter-points and a core somewhat smaller than a diameter represented by the distance between the inside cutter-points, thus affording 20 clearance and preventing sticking. Moreover, as the lateral play is controlled by the internal bore of the cutter-head as a whole the diameter of the core can likewise be controlled. Said core can consequently be made 25 small enough to enter the core-barrel, as the side shifting will permit the inner teeth to operate beneath the lower end of said barrel.

Another advantage is gained by the particular construction of the teeth. It will be 30 observed that each tooth member is separated from the adjacent tooth member by a deep notch 17, and the teeth on each member are formed by an intermediate notch 18 of less depth than the notches 17. The right- 35 hand edges 20 of the teeth are substantially vertical, while the left-hand edges 21 are inclined, and it is to be observed that the pitch of the edges 21 is opposite to the pitch of the screw-threads by which the cutter is held in 40 the casing. As a result every time the cutter points or teeth strike the rock they will tend to advance or revolve the cutter-head to the right, and the inertia of the casing and the parts carried thereby will consequently 45 tend to cause a relative rotation of the cutter, so as to effect the tightening movement at the joint, thus avoiding the danger of the parts unscrewing.

It will be observed that the inclined sides 50 of all of the teeth have an inclination in the same rotative direction and that the effect of the inclined sides of all the teeth is cumulative. In operation the material from in front of the vertical sides of the teeth is dislodged 55 or chiseled away, leaving the material beneath the inclined sides to form a series of inclined slides. Thus it will be seen that the cutter-points at the instant of impact with the bottom of the bore-hole will be given a 60 sort of corkscrew motion, enabling the points of the inwardly-set teeth 15 to more effectively trim or cut the core down to a size that will enter the core-barrel. The outwardly-set teeth 14 as a matter of fact do nearly all 65 of the cutting, and consequently the princi-

pal part of the above corkscrew effect is due to the inclination of the outwardly-set teeth 14, and it can be easily understood that the outwardly-set teeth operating at one side of the bore-hole may have more tendency to rotate or slide than those at the diametrically opposite side, and at the instant of impact if one of the sets of outwardly-set teeth should slide forward faster or farther than those at the opposite side of the bore-hole the effect 70 will be to carry one of the groups of inwardly-set teeth under the end of the core-barrel to more effectually trim the core down. Hence the inclined form of teeth shown clearly in Figs. 1, 2, 3, and 4, together with their distribution, forms an important part of this invention. 75

To fully understand the operation of the drill, it must be remembered that a reciprocating or percussion drill operated by a cable 80 will naturally jostle upon striking the rock or bottom of the drill-hole, and as a consequence the hole is of greater diameter than the drill. This is necessary in order to afford clearance and easy-working space for the drill. This 85 jostling action is taken advantage of in the present construction. It will be evident that when the outside cutter-teeth 14 strike the bottom of the channel they will leave the same after each stroke with high and low 90 places of irregular height and depth. Then in the great majority of instances at the next descent, having been slightly rotated by the action hereinafter described, one or the other of the outside sets of cutter-teeth will strike 95 a high place an instant before the corresponding set at the opposite side will strike. The downward force of the drill will throw the striking-teeth forward, while at the same time the inertia of the drill will momentarily 100 hold the said opposite teeth against a like forward movement. Now owing to the slight clearance outside the outer cutter-teeth, the set which has struck the high place, as above, 105 will describe a portion of a circle whose center for the instant is the corresponding opposite set. This swinging or rotary movement, as will be evident, will carry one of the inner sets of teeth 15 beneath the core-barrel, so 110 that it will engage and trim down the core; 115 but as the said swinging movement of the drill will be limited by the core-barrel the trimming action will just be sufficient to permit the core to pass into said barrel. At the next stroke the swinging movement above 120 described may be in an opposite direction. As a matter of fact there will be only a very small part of a circle (five to ten degrees) 125 described by the forward or lateral motion of the teeth 14 at each stroke; but it is abundantly sufficient to carry the inside cutter-teeth 15 under the end of the core-barrel and cause them to trim the core down small enough to enter the barrel. These motions are what are termed the "jostle," and it is 130

this which makes the tool as a whole successfully operative. In this connection it is to be noted that the rear edges of the teeth are set at an angle of over fifty degrees from the 5 perpendicular. This is of great importance, for if disposed at much less of an angle there would be no forward movement, and if the teeth were not broken by the impact each would in all probability dig a hole for itself, 10 and the desired results would not be obtained. The arrangement of the teeth ninety degrees apart, or, in other words, the placing of the corresponding teeth one hundred and eighty degrees apart, is of great importance. If, 15 for instance, there were three sets of outer teeth at one hundred and twenty degrees apart, or a greater number at a less number of degrees apart, they would so brace and counteract each other that the drill as a 20 whole would be very apt to at all times remain substantially concentric to the bore-hole, and the necessary lateral swing could not be obtained.

From the foregoing it is thought that the 25 construction, operation, and many advantages of the herein-described invention will be apparent to those skilled in the art without further description, and it will be understood that various changes in the size, shape, 30 proportion, and minor details of construction may be resorted to without departing from the spirit or sacrificing any of the advantages of the invention. Thus the drawings herewith show a total of eight cutter-points arranged in four groups of two each, 35 and while in practice this is found to be the best number of cutter-points yet it will be observed that each of the four groups of teeth may consist of one, two, three, or more, 40 cutter-points, and also it may be observed that the cutter-points or some portion of them can be formed with chisel edges at right angles to those shown in the drawings, and indeed in some particular formations this latter shape of cutter-point is better. 45

All of the above variations can be made without departing in the least from the spirit of the invention.

Having thus fully described my invention, 50 what I claim as new, and desire to secure by Letters Patent, is—

1. A percussion or reciprocatory core-cutter comprising a body having a plurality of depending tooth members, the members of 55 each set being diametrically opposite, and the members of the different sets being disposed on the body at points substantially ninety degrees apart, the tooth members of one set of members extending inwardly and 60 those of the other set extending outwardly.

2. A percussion or reciprocatory core-cutter comprising a body having a plurality of depending tooth members, the members of each set being diametrically opposite and the 65 members of the different sets being disposed

on the body at points substantially ninety degrees apart, the tooth members of one set of members extending inwardly and those of the other set extending outwardly, said tooth members each having a group of teeth. 70

3. A percussion or reciprocatory core-cutter comprising a tubular body having depending tooth members located at points substantially ninety degrees apart, said members being alternately set inwardly and outwardly. 75

4. In a percussion or reciprocatory core-drill, the combination with a core-receiving barrel, of a drill surrounding the same and laterally movable with respect thereto, and core-trimming teeth carried by the lower end of the drill and having cutting edges at their lower ends that operate beneath the core-barrel upon the lateral movement of the drill. 80

5. In a percussion or reciprocatory core-drill, the combination with a core-receiving barrel, of a drill surrounding the same and laterally movable with respect thereto, and inwardly set pointed core-trimming teeth carried by the lower end of the drill and having cutting edges at their lower ends that operate beneath the barrel, the inward movement of the teeth being limited by the core-barrel. 85

6. A percussion or reciprocatory core-cutter, comprising a body having a plurality of depending sets of tooth members, the members of each set being diametrically opposite, and the members of the different sets having 90 their central portions disposed substantially ninety degrees apart, the tooth members of one set extending inwardly and those of the other set extending outwardly, said tooth members each having a plurality of teeth, 95 and the teeth of each member extending in the same direction. 100

7. A percussion or reciprocatory core-cutter, comprising a tubular reciprocatory stem, a core-barrel member slidably mounted therein, said stem being capable of a lateral movement with respect to the barrel, and a percussion-cutter carried by the lower end of the stem and having inwardly-extending teeth that are capable of lateral movement with 110 said stem to positions beneath the lower end of the core-barrel to trim the core beneath the said barrel. 115

8. The combination with a tubular reciprocatory stem, of a core-barrel slidably mounted therein, said stem being capable of a lateral movement with respect to the barrel, and a percussion-cutter carried by the lower end of the stem and including a tubular body having diametrically opposite inwardly-extending teeth that are capable of lateral movement with the stem and with respect to the barrel to positions beneath the lower end of the core-barrel to trim the core 120 beneath said barrel. 125

9. The combination with a tubular reciprocatory stem, of a core-barrel slidably mounted therein, said core-barrel being of less diameter than the bore of the stem, said 5 stem thus being capable of a lateral movement with respect to the barrel, and a percussion-cutter carried by the lower end of the casing and including a tubular body having diametrically opposite tooth members, each 10 member including a plurality of adjacent teeth inclined inwardly and capable of lateral movement with the stem to positions beneath the lower end of the core-barrel to trim the core beneath the same.
- 15 10. The combination with a tubular reciprocatory stem, of a core-barrel slidably mounted therein, said stem being capable of a lateral movement with respect to the barrel, and a percussion-cutter carried by the lower 20 end of the stem and comprising a body having a plurality of depending sets of tooth members, the members of each set being diametrically opposite and the members of the different sets having their central portions disposed substantially ninety degrees apart, the tooth members of one set extending inwardly and being capable of a lateral movement with the stem and with respect to the barrel to positions beneath the lower end of 25 the core-barrel, the members of the other set extending outwardly.
11. The combination with a stem, of a cutter threaded on the stem and having depending teeth, said teeth having substantially 30 vertical sides and inclined sides, the latter sides being inclined in an opposite direction to the threads of the joints.
12. The combination with a reciprocatory tubular stem, of a cutter comprising a tubular body threaded on the stem and having depending inwardly and outwardly extending teeth, said teeth having substantially 35 vertical sides, and inclined sides, the latter sides being inclined in an opposite direction to the threads, and a core-barrel slidably mounted in the stem, said stem and teeth being capable of a lateral movement with respect to the barrel.
13. In a percussion or reciprocatory core- 40 drill, the combination with a core-barrel, of a reciprocatory drill-stem surrounding the same and laterally movable with respect thereto, cutting-teeth carried by the lower end of the stem, and inset core-trimming teeth also carried by the lower end of the stem and swinging beneath the core-barrel on the lateral movement of the stem.
14. In a percussion or reciprocatory core-

drill, the combination with a core-barrel, of a reciprocatory drill-stem surrounding the 60 same and laterally movable with respect thereto, outside cutting-teeth carried by the lower end of the stem, and inset core-trimming teeth also carried by the lower end of the stem and swinging beneath the core-barrel 65 on the lateral movement of said stem.

15. In a percussion or reciprocatory core-drill, the combination with a core-barrel, of a reciprocatory drill-stem surrounding the same and laterally movable with respect 70 thereto, outside cutting-teeth carried by diametrically opposite portions of the lower end of the stem, and inset core-trimming teeth disposed between the cutting-teeth and also carried by the lower end of the stem, said inset teeth swinging beneath the core-barrel on the lateral movement of the stem.

16. In a percussion or reciprocatory core-drill, the combination with a core-receiving barrel, of a reciprocatory stem surrounding 80 the same and capable of lateral movement with respect thereto, and teeth rigidly carried by the lower end of the stem and operating beneath the core-barrel to trim a core to pass into said barrel.

17. In a percussion or reciprocatory core-drill, the combination with a core-receiving barrel, of a reciprocatory stem surrounding the same and capable of lateral movement with respect thereto, outstanding teeth rigidly carried by the lower end of the stem, and inset teeth rigidly carried by the lower end of the stem and operating beneath the core-barrel to trim a core to pass into said barrel.

18. In a percussion or reciprocatory core-drill, the combination with a core-barrel, of a reciprocatory drill-stem surrounding the same and laterally movable with respect thereto, outside cutting-teeth carried by diametrically opposite portions of the lower end 90 of the stem, said teeth having rear edges that are disposed at an inclination to produce a rotary movement of said cutter upon its impact with the bottom of the bore-hole, and inset core-trimming teeth carried by the lower end of the stem and swinging beneath the core-barrel on the lateral movement of said stem.

In testimony that I claim the foregoing as my own I have hereto affixed my signature in 100 the presence of two witnesses.

ROBERT M. DOWNE.
